UNITED STATES PATENT OFFICE.

WILLIAM S. SNYDER, OF NASHVILLE, TENNESSEE.

HYDRANT.

1,345,465.

Specification of Letters Patent.

Patented July 6, 1920.

Application filed July 3, 1919. Serial No. 308,394.

To all whom it may concern:

Be it known that I, WILLIAM S. SNYDER, a citizen of the United States, and a resident of Nashville, in the county of Davidson 5 and State of Tennessee, have invented certain new and useful Improvements in Hydrants, of which the following is a specification.

My invention is an improvement in hydrants, and has for its object to provide a hydrant wherein the valve controlling the flow of water is normally spring closed, and is controlled to opening position by the action of the hose connection.

15 A further object is to provide a hydrant having drainage, and wherein all of the parts may be removed for repair or inspection, and wherein such parts are protected from freezing.

20 In the drawings:—

Figure 1 is a vertical section of the improved hydrant,

Figs. 2 and 3 are sections on the lines 2—2, and 3—3, respectively of Fig. 1,

25 Fig. 4 is a top plan view with the cover opened,

Fig. 5 is a perspective view of the hose connection,

Fig. 6 is a similar view of the valve.

30 In the present embodiment of the invention, a suitable casing 1 is provided for housing the working parts of the hydrant, and this casing which is adapted to be inserted in the ground to a suitable depth has 35 a top or head 2 which is provided with a cover 3 hinged thereto for closing the top of the hydrant. At its lower end, a cup shaped extension 4 is connected with the casing 1, and this extension houses the elbow 40 5 which connects the hydrant with the water main.

As shown, this elbow has a marginal flange 6 at its outer end, which fits between the extension 4 and the bottom of the casing 1, and the casing has threaded engagement 45 with an upstanding rib 7 on the flange. The elbow has a threaded stem 8, which extends through an opening in the bottom of the cup shaped extension, and is engaged by a nut 9 to secure the extension to the casing 50 1 and to the elbow.

The opening in the upper end of the elbow 5 is reduced and internally threaded, to receive a threaded nipple 10 on the lower 55 end of a reduced connection 11, which con-

ncts the elbow with the body 12 of the hydrant. An annular shoulder 13 is provided between the union and the nipple which engages the upper end of the elbow, and the upper end of the union has an upstanding flange 14 into which the lower end of the body 12 is threaded.

A partition 15 at the upper end of the union has a central opening, through which is slidable, the tubular valve 16—17. This 65 valve consists of two portions of unequal diameter, the portion 17 being of greatest diameter and having a port or ports 18 which when below the partition 15 permit the water to flow into the valve and through 70 the same to the hose.

A coil spring 19 encircles the valve within the union, between an internal annular shoulder in the union and a nut 21 threaded on the portion 16 of the valve. Above this 75 nut and between the same and the annular shoulder between the portions 16 and 17 of the valve, there is arranged a pair of oppositely disposed concave washers 22 and 23, and the under end of the opening 80 through the partition 15 is counter-bored to receive the upper face of the washer 22 which co-operates with the counter-bore to seal the opening through the partition.

It is the portion 17 of the valve which 85 slides in the opening of the partition, and the coil spring will normally hold the valve with the openings 18 above the partition, and with the opening through the partition sealed by a washer 22. The upper end of 90 the portion 17 of the valve is threaded into a tubular casing 24, which at its upper end has a cap 25 provided with a reamed opening 26. With this opening is adapted to engage the beveled lower end of one arm 95 27 of an elbow —27—28. The other arm 28 of the elbow is adapted for engagement by a hose.

The arm 27 of the elbow has a fixed collar 29 thereon, and this collar has oppositely 100 extending pins 30 which are adapted to engage beneath an inwardly extending web 31 on an extension 32 from a catch 33 which is threaded onto the upper end of the body 12 of the hydrant. These webs are 105 shaped, and are spaced apart at their ends so that the pins may pass between them and engage between the webs.

A washer 34 encircles the body of the hydrant, within the bowl 2, forming a seal at 110

this point, and the body of the hydrant, the flange 6 and the bottom of the extension 4 have openings 35, 36, and 37 respectively, to provide drainage from the body of the 5 hydrant.

The extension 4 has a vertical slot 38 for the lateral arm of the elbow 5, which permits the extension to be placed over the elbow. The extension 32 is polygonal in cross section in order that a wrench may be engaged therewith, and the threads which connect the nipple 10 with the elbow are left hand threads, all of the others being right hand. Thus when a wrench is engaged with the 10 extension 32, the entire hydrant construction including the union 11 may be detached from the elbow and removed from the casing for any purpose desired. The elbow 5 may also be removed when the hydrant is removed.

The casing 1 protects the hydrant from dirt, forming an inclosing casing for the same and also protects it from freezing. In use, when it is desired to provide water, the lid or cover 3 is raised, and the arm 27 of the elbow 27-28 is thrust through the extension 32 and the cap 33, until the beveled lower end thereof engages the cap 25. The elbow is now given a quarter turn, causing 25 the pins to engage beneath the webs of the extension.

The inward thrusting of the arm 27 of the elbow forces the valve 16-17, and the tubular casing 24 downward, bringing the 30 opening 18 below the partition 15. The water now flows freely through the valve, the tubular casing 24, the elbow and the hose. When the elbow 27-28 is released, the spring forces the valve upward, tightly 35 sealing the hydrant. Any waste water within the body 12 of the hydrant may drain away through the openings 35, 36, and 37.

I claim:—

1. A hydrant, comprising a union for connection with the main, said union having at its upper end a transverse partition provided with a central opening, a tubular valve slideable in the opening, and having lateral ports, a spring normally pressing the valve 40 upward to bring the ports above the parti-

tion and to prevent the flow of water into and through the valve, the lower end of the valve being closed, an extension connected with the upper end of the valve and having a beveled seat at its upper end, a hose connection having its end beveled to engage the seat, and a casing inclosing the valve, the spring, and the extension and having an opening for receiving the connection, said connection and extension having interengaging means for holding the valve open. 55

2. A hydrant comprising a union for connection with the main, and having at its upper end a transverse partition provided with an opening, a tubular valve slideable in the 60 opening and having a lateral port, a spring normally pressing the valve upward to bring the port above the partition to prevent the flow of water through the valve, a casing inclosing the valve, a union for connection with the valve, and an interlocking connection between the union and the casing for holding the valve open when the union is engaged with the valve, and an inclosing casing for drain openings. 65

3. A hydrant comprising a union for connection with the main, and having at its upper end a transverse partition provided with an opening, a tubular valve slideable in the opening and having a lateral port, a spring normally pressing the valve upward to bring the port above the partition to prevent the flow of water through the valve, a casing inclosing the valve, a union for connection with the valve, and an interlocking connection between the union and the casing for holding the valve open when the union is engaged with the valve. 75

4. In a hydrant, a valve for controlling the flow of the water and movable longitudinally of the hydrant into open and closed position, a spring normally holding the valve in outward closed position, and a union, said valve having means for engagement by the union to move the valve into open position, a casing for the valve, and interlocking mechanism in connection with the casing and the union for holding the union with the valve open. 80

WILLIAM S. SNYDER.
